SASH HOLDING DEVICE

Filed Oct. 22, 1931

FIG. 1.

FIG. 2.

9 6" *H. G. Kimbro* Inventor

By Watson E. Coleman
Attorney

UNITED STATES PATENT OFFICE

HUBERT G. KIMBRO, OF BELL, CALIFORNIA

SASH HOLDING DEVICE

Application filed October 22, 1931. Serial No. 570,467.

This invention relates to sash holding devices and pertains particularly to a device which will operate automatically to maintain a window sash in any raised position.

5 The primary object of the present invention is to provide a spring-pressed device which is carried by a window sash for engagement with the adjacent side of the window frame for the purpose of frictionally 10 maintaining the sash in any position to which it is moved.

Another object of the invention is to provide a sash holding device which is hidden from view and which may be installed without 15 making any changes in the construction of the window frame, as is necessary in the use of weight devices which are attached by cords which pass into the interior of the window frame over supporting pulleys.

20 The invention broadly contemplates the provision of one or more friction plates which are set into recesses in the side edges of the window sash and which are normally forced outwardly by springs lying therebeneath 25 into engagement with the adjacent wall of the window frame. The frictional contact between these plates and the window frame wall is sufficient to retain the sash in any position to which it may be moved, 30 but is not great enough to interfere with the movement of the sash to open or closed position.

The invention will be best understood from a consideration of the following detailed description taken in connection with the accompanying drawing forming part of this specification, with the understanding, however, that the invention is not confined to any strict conformity with the showing of 40 the drawing but may be changed or modified so long as such changes or modifications mark no material departure from the salient features of the invention as expressed in the appended claim.

45 In the drawing:—

Figure 1 is a view of one side edge of a window sash, the central portion of which has been broken away, showing a pair of holding devices embodying the present invention mounted in suitable recesses therein.

Figure 2 is a view in front elevation of a portion of one side of a sash, and a portion of the adjacent frame showing one of the devices embodying the invention in operative position, the section of the sash being taken on line 2—2 of Figure 1, and

55 Figure 3 is a view of the rear face of the sash holding device per se.

Referring now more particularly to the drawing, wherein like numerals of reference 60 indicate corresponding parts throughout the several views, the numeral 1 indicates generally a window sash, a portion of one side bar thereof being indicated by the numeral 2. The usual channel in which the sash side 65 bar works is indicated by the numeral 3 and a portion of the frame in which the channel is formed is indicated generally by the numeral 4.

The present sash holding device consists of 70 an elongated plate 5 which has a sleeve 6 formed transversely of one end and disposed upon one face thereof which is the back face of the plate when the same is in use. This sleeve has one end flush with one longitudinal 75 edge of the plate while the other end terminates short of the opposite longitudinal edge as shown in Figure 3 and each longitudinal edge of the plate has a rearwardly extending flange 6' and these flanges are connected by 80 a similar flange 6'' which is disposed at the end opposite the end upon which the sleeve 6 is formed. It will thus be seen that the longitudinal flange 6' is separated at one end from the adjacent end of the sleeve 6 forming the 85 space 7. Disposed transversely of the back face of the plate 5 is a coil spring 7' which is of a length less than the width of the plate so that it will fit between the longitudinal flanges 6'. The ends of these coil springs are 90 extended in opposite directions as indicated at 8, the extensions terminating in inwardly directed arms 9 one of which, as shown, extends into the sleeve 6 from the end adjacent the space 7, the other end lying upon and 95 sliding on the back face of the plate, in the manner shown.

In the installation of the sash holder, the lateral face of the side bar 2 is provided with a suitable recess or pocket 10 to receive the 100

plate 5, and the bottom of this pocket has formed transversely thereof and substantially midway between its ends the groove 11 for the reception of the coil spring 7'.

From the foregoing, taken in connection with the showing of Figure 2 of the drawing, it will be readily seen that when the sash is in position in the window frame, the spring 7', through the medium of the extended arms 8 and 9, forces the friction plate out of the recess 10 against the bottom of the channel 3 in which the bar 2 moves and a resistance will thus be set up to the free movement of the sash in the frame so that after it has been shifted, it will be held in a position to which it is moved by the frictional engagement of the plate, or plates where several are used on one sash, with the adjacent frame.

It will also be apparent from the foregoing that one or more of the present devices may be readily attached to a window sash and the sash installed in its frame without the necessity of making changes which are now necessary where weight controlling devices are employed.

Having thus described the invention, what is claimed is:—

A window sash holding device, comprising an elongated friction plate having a sleeve formed transversely of one end, a coil spring disposed transversely of said plate substantially midway between its ends, said spring having its ends extended in opposite directions and longitudinally of the plate and each terminating in an arm extending transversely of the plate, one of said arms being mounted in said sleeve, said device being designed to be mounted in one side of a sash bar and said spring operating to force the plate outwardly for frictional engagement with the adjacent frame.

In testimony whereof I hereunto affix my signature.

HUBERT G. KIMBRO.
